WRITING MACHINE PLATEN ROLL

John Q. Sherman, Dayton, Ohio

Application June 4, 1932, Serial No. 615,402

56 Claims. (Cl. 197—133)

This invention relates to writing machines, and more particularly to a platen roll therefor, capable of being easily and quickly transformed from a positive feed pin type device into a smooth roll 5 having an unbroken surface for friction feed operation and vice versa.

The platen roll, forming the subject matter hereof, incorporates the desirable features of both a smooth roll and a pin type roll by providing 10 feeding pins which, at will, may be wholly retracted within the roll and the roll adjusted to completely close the spaces previously occupied by such feeding pins.

The present construction is a further development 15 and amplification of that described and claimed in copending application, Serial No. 542, 855, filed June 3, 1931.

The object of the invention is to improve the construction, as well as the means and mode of 20 operation of platen rolls for writing machines whereby they will not only be inexpensive in construction, but will be more efficient in operation, uniform in action, readily interchangeable with the platen rolls of writing machines, and 25 unlikely to get out of repair.

A further object of this invention is to provide 30 a platen roll for a writing machine which may be readily and easily transformed from a positive pin feed type to a smooth friction type device and vice versa.

A further object of the invention is to provide 35 automatically reciprocatory feeding pins and a retractable mounting therefor by which the feeding pins may be contained wholly within the platen roll or progressively projected therebeyond as operating conditions may require.

With the above primary and other incidental 40 objects in view, as will more fully appear in the specification, the invention consists of the features of construction, the parts and combinations 45 thereof, and the mode of operation, or their equivalents, as hereinafter described and set forth in the claims.

Referring to the accompanying drawing, 50 wherein is shown the preferred, but obviously not necessarily the only form of the embodiment of the invention, Fig. 1 is a transverse sectional view through the traveling carriage and platen roll of a conventional form of typewriter to which the present invention has been applied and 55 wherein the feeding pins are shown in operative position for positively advancing record strips, being fed about the platen roll, by engagement in marginally punched holes provided therein. Fig. 2 is a similar view showing the feeding pins wholly retracted within the platen roll and the

parts in condition for friction feeding of the record strips. Fig. 3 is a longitudinal sectional view of the platen roll. Fig. 4 is an enlarged detail sectional view of one end of the platen roll, showing the parts adjusted for positive feeding 60 engagement of the pins with the record material. Fig. 5 is a detail side view of the mounting disc or grooved guiding head for the feeding pins. Figs. 6 and 7 are respectively front and side views of the adjustable actuating cam for the retractable feeding pins, showing the cam in its extended condition for projecting the pins progressively beyond the periphery of the platen roll. Figs. 8 and 9 are similar views showing the actuating 65 cam in its retracted condition whereby the feeding pins are maintained within the platen roll. Figs. 10 and 11 are detail front and side views respectively of the main or stationary portion of the actuating cam. Figs. 12 and 13 are front and side views respectively of the adjustable or retractable portion of the actuating cam. Figs. 14 and 15 are detail sectional and front views respectively of a modified form of actuating cam.

Like parts are indicated by similar characters of reference throughout the several views.

Referring to the drawing, 1 is the frame of the traveling carriage of a conventional form of writing machine of which 2 is the paper guide and 3 the rotary platen, about which superposed strips or sheets of writing material are progressively advanced past the writing or impact point of the movable type bars 5. Located beneath the platen roll 3 are the usual friction feed rollers 6—6 mounted for movement into and out of frictional engagement with the periphery of the platen roll 3 by the adjustment of the finger trip lever 7 interconnected by a link 8 with the adjustable mounting of the friction rollers 6. This construction is such that so long as the trip lever 7 is elevated, as shown in Fig. 2, the friction feed rollers 6 will have operative feeding engagement with the periphery of the platen roll 3 to hold the record strips or sheets 4 in contact therewith and effect progressive advancement of such writing material as the platen roll 3 is rotated. 90 By depressing the lever 7 to the position shown in Fig. 1, the mounting mechanism of the friction rollers 6 is adjusted to withdraw the rollers 6 from their operative relation with the platen roll 3 thereby leaving the record material 4 free for adjustment relative to the platen roll or free for 95 advance feeding movement under the influence of other positive type feeding means.

As thus far described, the construction is that 100 of a conventional typewriter of popular manu-

facture and, per se, forms no part of the present invention, but has been shown and described merely for illustrative purposes in order that the construction and operation of the platen roll, 5 forming the subject matter hereof, may be better understood.

The platen roll 3 comprises a cylinder or sleeve 3' having at each end thereof a radially grooved mounting disc or head 9 mounted upon the usual 10 trunnion shaft 10 journaled in the traveling carriage 1 and carrying at its extremities the knobs 11 for manual rotation of the platen roll.

The mounting heads 9 are disposed with their radially grooved faces outwardly. Within the 15 grooves 12 are mounted for radial reciprocatory movement a series of feeding pins 13, the outer ends of which are tapered for free and easy engagement in holes punched in the record material 4.

Surrounding the shaft 10 beyond the cylinder heads 9, are stationarily held screw threaded sleeves 15 upon which are secured the actuating or control cams by which the feeding pins 13 are progressively extended and retracted as the 20 platen roll or cylinder is rotated. These cams comprise stationary portions 16 fixedly secured upon the mounting sleeve 15 and having thereon a laterally projecting flange 17 which engages in notches 18 in the reciprocatory pins 13. 25 Mounted upon the stationary portion 16 of the cam structure is a movable section 19 slidable radially upon guides or ways 20 upon the stationary section 16 which engage within grooves 21 in such movable section. The movable section 30 19 also carries a laterally projecting flange 23 complementary to the flange 17 of the stationary cam section. The cam flanges 17 and 23 are beveled at their extremities and projecting into overlapping relation with each, both when 35 the movable section 19 is extended and retracted, as is shown in Figs. 6 and 8. The cam flange 17 of the stationary section 16 is substantially concentric with the shaft 10 as is also the cam flange 23 of the movable section 19 when the section 40 is in its retracted position, as shown in Fig. 8, but when extended as indicated in Figs. 1 and 6, this portion of the cam flange assumes an eccentric relation with the shaft 10. The overlapping beveled extremities of the flange portions 17 and 23 are of such length that the notched feeding pins 13 will pass onto one of these sections before entirely leaving the other section when the cam parts are extended.

Expansion springs 24 are interposed between 55 the stationary and movable sections 16 and 19 of the actuating cams. These springs tend to separate the respective sections of the cam into distended relation as is illustrated in Figs. 1 and 6.

The actuating cam structure and mounting sleeves 15 therefor are held stationary by arms 60 25 secured upon the sleeves by set screws 26, which arms 25 extend radially beyond the platen roll or cylinder and are transfixied by a transverse frame rod 27 of the traveling writing machine carriage 1.

The heads 9 being fixedly connected to the 70 shaft 10 and to the cylinder 3', and the feeding pins 13 being mounted within the radial grooves 12 of the heads 9, such pins are carried through a circuitous path of travel in unison with the rotation of the platen roll or cylinder. The laterally projecting guide flanges 17 and 75 23 of the cam sections 16 and 19 having engagement in the lateral notches 18 of the pins, de-

termine the particular shape or course of such circuitous path of travel. When the movable section 19 is retracted, as illustrated in Figs. 2 and 8, the pins will follow a uniform circular path of such radius that the tapered ends of the pins 13 will be maintained within the peripheral outline of the cylinder. However, when the adjustable section 19 of the controlling device is distended by the springs 24, the portion of the guide flange 23 carried thereby will be eccentric and will transmit to the feeding pins 13 a correspondingly eccentric path of travel wherein the pins will be radially projected beyond the peripheral contour of the cylinder during their passage over such eccentrically positioned portion 23 of the guide flange. This causes the pins 13 to be progressively extended and retracted as the cylinder is rotated. The cam portions 16 and 19 and their mounting sleeves 15 are so positioned rotatively that the feeding pins 13 will be projected into operative engagement with the record material either approximately at the writing position or after the material has passed slightly beyond the writing position, as is illustrated in Fig. 1. The shape of the guide flange 100 is such that as one pin is being extended or projected outwardly into engagement with the paper, other pins are being correspondingly retracted out of such engagement so that but few pins are simultaneously engaged therewith. 105

An arm 28 pivoted upon the carriage rod 27 carries a retainer plate or head 29 which overlies the writing material or record strips adjacent to the point of engagement of the feeding pins 13 to loosely retain such strips in operative engagement with the pins. This retainer carrying arm 28 is provided with a shoulder 30 to be engaged by a detent 31 to temporarily hold the arm 28 and retainer head in elevated position. The detent 31 is provided with a trip arm 32 by 110 which it may be easily and quickly disengaged from the shoulder 30 to release the arm 28 and permit the return of the retainer plate or head 29 into operative relation with the record material and feeding pins. 115

When it is desired to dispense with positive feeding of the record material and to employ the auxiliary friction rollers 6 for feeding the record material about the platen roll, the movable section of the actuating cam is depressed against 120 the tension of its springs 24 to the position shown in Figs. 2 and 8, and terminal caps 35, screw threaded upon the mounting sleeves 15 at each end of the cylinder, are adjusted axially thereon into abutting relation with the ends of the cylinder 3 as is shown in Fig. 3 wherein the marginal flanges of the terminal caps 35 overhang the ends of the feeding pins 13, thus maintaining the feeding pins retracted wholly within the cylinder and presenting a smooth unbroken surface over which the writing operation is to be carried on. The terminal caps 35 are provided with knurled portions 36 to facilitate their rotative adjustment upon the mounting sleeve 15. When the feeding pins 13 have been retracted 125 and the terminal caps 35 adjusted into close abutting relation with the ends of the cylinder 3, the latter becomes in effect a conventional form of smooth writing machine platen with which the auxiliary friction rollers 6 co-operate 130 to frictionally feed the writing material about the platen roll in the ordinary manner. However, by adjusting these terminal caps 35 outwardly upon their mounting sleeves 15 to again uncover the feeding pins 13, the springs 24 by 135 140 145 150

their expansion will automatically project the removable section 19 of the controlling device radially outwardly upon the guides or ways 20 thereby causing the guide flange portion 23 to 5 assume an eccentric relation and cause the feeding pins to be progressively projected beyond the peripheral contour of the cylinder through the space intermediate the terminal caps 35 and the end of the cylinder 3. Suitable set screws 26 are 10 loosened, permitting the terminal caps 35 to rotate with the platen when the feeding pins 13 are wholly retracted within the cylinder, as disclosed in Fig. 3. When the terminal caps 35 are adjusted outwardly as disclosed in Fig. 4, the set 15 screws 26 engage recesses in the sleeve 15 so as to lock the sleeve 15 in a fixed relation with respect to the typewriting machine, thereby causing the pins to extend beyond the periphery of the platen in the proper position to engage the writing material. When the sleeve 15 is held in a fixed position with respect to the typewriting machine, the terminal caps 35 do not rotate with the platen as these are carried by the sleeve 15.

In the modification disclosed in Figs. 14 and 25 15, the movable cam section 19 may be retracted by a rotary mechanism which includes a pin 40 seated in a suitable aperture 42 in the cam sector 19 having the other end extending into a cam groove 44 located in the screw threaded 30 member 46 threadedly engaging a collar 48 fixedly attached to the sleeve 51 mounted on the shaft 10.

As may best be seen from Fig. 15, the location of member 46 will cause the end of pin 40 to 35 move either towards or away from the center of the shaft, as the case may be, as the end of pin 40 will follow the cam groove 44. Instead of the terminal cap 35 being screw threaded upon the sleeves 15, as disclosed in Fig. 4, suitable cylindrical caps 50 are screw threaded to 40 the rotary member 47 carried by the shaft 10 so that when member 46 is rotated to retract the section 19, the cylindrical caps 50 may be rotated with respect to member 47 so as to completely 45 cover the path of the pins 13, concealing the pins the same as in Fig. 3.

From the foregoing it is apparent that the section 19 may be withdrawn by rotating member 46 so as to withdraw the pins 13 from the 50 periphery of the groove, and the path of the pins may be completely covered by rotating the circular sleeves 50 in the proper direction so as to have these advance over the paths of the pins. When it is desired to again use the pin 55 feeding mechanism, the cylindrical sleeve 50 is rotated in the opposite direction so as to move outwardly to permit the pins 13 to extend into slots formed intermediate the cylindrical sleeve 50 and the platen roller. When this has been 60 done, member 46 may be rotated through 180 degrees so as to permit the section 19 to advance to the out position, thereby causing the pins 13 to extend beyond the periphery of the platen. In this modification, during operation of the 65 typewriter the cylindrical cap rotates with the platen when in extended and contracted relation. In other respects the above modification operates in the manner similar to that disclosed in the preferred modification disclosed in Fig. 1.

70 From the above description it will be apparent that there is thus provided a device of the character described possessing the particular features of advantage before enumerated as desirable, but which obviously is susceptible of 75 modification in its form, proportions, detail con-

struction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. In a writing machine, a rotary platen, a pin wheel feeding mechanism associated with said rotary platen, said pin wheel feeding mechanism having an operative and an inoperative position, the pins of said pin wheel feeding mechanism extending through the periphery of the platen when in operative position, and means for holding the pins in either position, said means including a shield for sealing the pins within the periphery of said platen when in inoperative position. 100

2. In a writing machine, a platen, a pin wheel feeding mechanism for advancing the writing material past said platen, said pin wheel feeding mechanism having an operative and an inoperative position, a shield completely enclosing said pins when in inoperative position, and auxiliary feeding means for advancing the writing material past the platen when said pin wheel feeding mechanism is in inoperative position. 105

3. In a writing machine, a platen, a positive feeding mechanism for advancing the writing material past said platen, said positive feeding mechanism having an operative and an inoperative position, a shield completely enclosing said positive feeding mechanism when said positive feeding mechanism is in inoperative position, and auxiliary feeding means for advancing the writing material past the platen when said positive feeding mechanism is in inoperative position. 115

4. A pin wheel feeding mechanism for advancing writing material past the platen, said pin wheel feeding mechanism including rotatively mounted pins and a cam mechanism for causing the pins to extend beyond the periphery of the platen, said cam mechanism including a stationary cam and a movable cam, said movable cam having an out position and a retracted position, the pin wheel feeding mechanism being inoperative when said movable cam is in retracted position. 125

5. A pin wheel feeding mechanism for a rotary platen, said pin wheel feeding mechanism including a pair of cam sectors, one of which includes an arcuate cam surface concentric with the 135 platen, the other sector having an out position and an in position, said other sector when in in position having its cam surface substantially concentric with the stationary cam surface, and when in out position cooperating with the stationary cam surface to form a substantially oval cam surface. 140

6. A pin wheel feeding mechanism for a rotary platen, said pin wheel feeding mechanism including pins carried by said platen, and a pair of 145 cams for positioning the pins with respect to the periphery of the platen, one of said cams causing the pins to travel in a path concentric with and within the periphery of said platen, the other cam having two positions, one of which causes 150

- the pins to travel in a substantially circular path, and the other of which causes the pins to extend beyond the periphery of the platen so as to engage the writing material.
5. 7. In a pin wheel feeding mechanism for a rotary platen, said pin wheel feeding mechanism including a plurality of feeding pins arranged radially in said platen and a pair of cams for positioning the pins with respect to the periphery of the platen, one of said cams including an arcuate portion for causing the pins to travel in an arcuate path within the periphery of the platen, the other cam having two positions, one of which causes the pins to travel in a circular path within the periphery of the platen and the other causing the pins to extend through the periphery of the platen so as to engage the writing material, and resilient means for biasing said movable cam into one of said positions.
10. 8. A pin wheel feeding mechanism for a rotary platen, said pin wheel feeding mechanism including feeding pins radially disposed with respect to the platen, a pair of cams, one of which causes the pins to travel in an arcuate path within the periphery of said platen, and the other having two positions, one of which causes the pins to travel exclusively within the periphery of the platen and the second position causing the pins to project beyond the periphery of the platen, 15 resilient means for biasing said cam into one of said positions, and positive means for holding the cam in the other position.
15. 9. A pin wheel feeding mechanism for a rotary platen, said pin wheel feeding mechanism including a plurality of pins radially disposed with respect to said platen, a pair of cams for positioning the pins with respect to the periphery of the platen, one of said cams having a cam surface causing the pins to travel in an arcuate path 20 within the periphery of the platen, the other of which has an out position and an in position, the in position causing the pins to travel in a substantially circular path within the periphery of the platen, and the out position causing the pins to extend beyond the periphery of the platen for engaging the writing material, and resilient means for biasing said cam into the out position.
25. 10. In a pin wheel feeding mechanism for a rotary platen, a plurality of pins radially disposed with respect to said platen, a pair of cams for controlling the path of said pins, one of said cams causing the pins to travel in an arcuate path within the periphery of the platen, the other cam having an out position and an in position, said other cam when in the out position causing the pins to extend beyond the periphery of the platen so as to engage the writing material, and when in the in position causing the pins to travel in a substantially circular path within the periphery of the platen, and positive means for holding the second cam in the in position.
30. 11. In a pin wheel feeding mechanism for a rotary platen, said feeding mechanism including a plurality of pins radially disposed with respect to the platen, a pair of cams for controlling the path of said pins, one of said cams causing the pins to travel in a substantially arcuate path within the periphery of the platen, the other cam having an out position and an in position, said other cam when in the out position causing the pins to extend beyond the periphery of the platen so as to engage the writing material, and when in the in position causing the pins to travel in a substantially circumferential path within the periphery of the platen, and a member for con-
- fining the pins within the platen and for holding said movable cam member in the in position.
35. 12. In a pin wheel feeding mechanism for a rotary platen, said pin wheel feeding mechanism including a plurality of pins radially disposed with respect to the platen, and a plurality of cams, one of said cams causing the pins to travel in an arcuate path within the confines of the periphery of the platen, another cam having an out position and an in position, said other cam when in the out position causing the pins to extend beyond the periphery of the platen, and when in the in position causing the pins to travel in a substantially circumferential path within the platen, and a third cam for controlling the position of said second cam.
40. 13. A pin wheel feeding mechanism for a rotary platen, said pin wheel feeding mechanism including a plurality of radially disposed pins, a plurality of cams, one of said cams causing the pins to travel in an arcuate path within the periphery of the platen, a second cam having an out position and an in position, said second cam when in the in position causing the pins to travel in a substantially circumferential path exclusively within the periphery of the platen, a third cam for controlling the position of said second cam, and a shield associated with said third cam for housing the pins when said second cam is in the in position so as to present a continuous writing surface to the writing material.
45. 14. In a pin wheel feeding mechanism for a rotary platen, said pin wheel feeding mechanism including a plurality of pins radially disposed with respect to said platen, a plurality of cams, one of said cams causing the pins to travel in an arcuate path within the periphery of the platen, a second cam having an out position and an in position, said second cam when in the out position causing said pins to extend beyond the periphery of the platen, and when in the in position causing the pins to travel in a substantially circumferential path exclusively within the periphery of the platen, a third cam having an eccentric cam surface, and a cam follower carried by said second cam engaging the cam surface of said third cam so that the position of said second cam is governed by said third cam.
50. 15. In a writing machine, a feed roller, a pin wheel feeding mechanism associated with said roller, said pin wheel feeding mechanism having an operative and an inoperative position, the pins of said pin wheel feeding mechanism extending through the periphery of said roller when in the operative position, and means for holding the pins in either position, said means including a shield for housing the pins within the periphery of said roller when in the inoperative position.
55. 16. In a writing machine, a roller, a pin wheel feeding mechanism associated with said roller for advancing the writing material past the writing position, said pin wheel feeding mechanism having an operative and an inoperative position, a shield for enclosing said pins when in inoperative position, and auxiliary feeding means for advancing the writing material to the writing position when said pin wheel feeding mechanism is in inoperative position.
60. 17. In a writing machine, a plurality of feed rollers, a positive feeding mechanism for advancing the writing material past the writing position, carried by one of said rollers, said positive feeding mechanism having an operative and an inoperative position, a shield for housing said positive feeding mechanism when said positive
80. 85. 90. 95. 100. 105. 110. 115. 120. 125. 130. 135. 140. 145. 150.

- feeding mechanism is in inoperative position, and means for separating said rollers when said positive feeding mechanism is in operative position.
18. In a writing machine, a feed roller, a pin wheel feeding mechanism, carried by said feed roller, for advancing the writing material past writing position, said pin wheel feeding mechanism including rotatively mounted pins and a cam mechanism for causing the pins to extend beyond the periphery of said roller, said cam mechanism including a stationary cam and a movable cam, said movable cam having an out position and an in position, the pin wheel feeding mechanism being inoperative when said movable cam is in the in position, and auxiliary feeding means for advancing the paper past the writing position when said pin wheel feeding mechanism is in inoperative position. 80
19. In a writing machine, a roller, a pin wheel feeding mechanism carried by said roller, said pin wheel feeding mechanism including feeding pins radially disposed with respect to said roller, a pair of cams, one of which causes the pins to travel in an arcuate path within the periphery of said roller, and the other having two positions, one of which causes the pins to travel exclusively within the periphery of the roller, and the other causing the pins to project beyond the periphery of the roller, resilient means for biasing said cam into one of said positions, positive means for holding it in the other position, and an auxiliary roller cooperating with said first roller in advancing the writing material past the writing position when said pin wheel feeding mechanism is in inoperative position. 85
20. In a writing machine, a roller, a pin wheel feeding mechanism carried by said roller, said pin wheel feeding mechanism including a plurality of pins radially disposed with respect to said roller, a pair of cams for positioning the pins with respect to the periphery of the roller, one of said cams having a cam surface causing the pins to travel in an arcuate path within the periphery of the roller, the other cam having an in position and an out position, the in position causing the pins to travel in a substantially circular path within the periphery of the roller, and the out position causing the pins to extend beyond the periphery of the roller for engaging the writing material, resilient means for biasing said movable cam into the out position, and an auxiliary roller cooperating with said first roller in supplying the writing material to the writing position when said pin wheel feeding mechanism is in inoperative position. 90
21. In a writing machine, a roller, a pin wheel feeding mechanism associated with said roller, said pin wheel feeding mechanism including a plurality of pins radially disposed with respect to said roller, a pair of cams for controlling the path of said pins, one of said cams causing the pins to travel in an arcuate path within the periphery of said roller, the other cam having an out position and an in position, said other cam when in an out position causing the pins to extend beyond the periphery of the platen so as to engage the writing material, and when in an in position causing the pins to travel in a substantially circular path within the periphery of the platen, positive means for holding said second cam in the in position, and auxiliary rollers cooperating with said first roller to advance the writing material past the writing position when said pin wheel feeding mechanism is in inoperative position. 95
22. In a writing machine, a roller, a pin wheel feeding mechanism carried by said roller, said pin wheel feeding mechanism including a plurality of pins radially disposed with respect to said roller, a pair of cams for controlling the path of said pins, one of said cams causing the pins to travel in a substantially arcuate path within the periphery of the platen, the other cam having an out position and an in position, said other cam when in the out position causing the pins to extend beyond the periphery of the platen so as to engage the writing material and advance it beyond the writing position, and in the in position, causing the pins to travel in a substantially circumferential path within the periphery of the platen, and a member for confining the pins within the platen and for holding said movable cam member in the in position. 100
23. In a writing machine, a roller, a pin wheel feeding mechanism for said roller, said pin wheel feeding mechanism including a plurality of pins radially disposed with respect to said roller, and a plurality of cams, one of said cams causing the pins to travel in an arcuate path within the confines of the periphery of the roller, another cam having an out position and an in position, said other cam when in the in position causing the pins to travel in a substantially circumferential path within the periphery of said roller, and when in the out position causing the pins to extend beyond the periphery of the roller, and a third cam for controlling the position of said second cam. 105
24. In a writing machine, a roller, a pin wheel feeding mechanism associated with said roller, said pin wheel feeding mechanism including a plurality of radially disposed pins carried by said roller, a plurality of cams, one of said cams causing the pins to travel in an arcuate path within the periphery of the platen, a second cam having an out position and an in position, said second cam when in the in position causing the pins to travel in a substantially circumferential path within the periphery of said roller, a third cam for controlling the position of said second cam, a shield associated with said second cam for enclosing the pins when said second cam is in the in position, and auxiliary feeding means associated with said roller for advancing the writing material past the writing position when said second cam is in the in position. 110
25. In a writing machine, a feed roller, a pin wheel feeding mechanism associated with said roller, said pin wheel feeding mechanism including a plurality of pins radially disposed with respect to said roller, a plurality of cams, one of said cams causing the pins to travel in an arcuate path within the periphery of said roller, a second cam having an out position and an in position, said second cam when in the out position causing said pins to extend beyond the periphery of the platen, and when in the in position causing the pins to travel in a substantially circumferential path exclusively within the periphery of said roller, a third cam having an eccentric cam surface and a cam follower carried by said second cam engaging the cam surface of said third cam so that the position of said second cam is governed by said third cam. 115
26. In a writing machine, a roller, a pin wheel feeding mechanism associated with said roller, said pin wheel feeding mechanism including a plurality of pins radially disposed with respect to said roller, and a non-rotatable cam having an out position and an in position, said cam engaging the pins and causing the pins to move 120
- 130
- 135
- 140
- 145
- 150

in a path within the periphery of the roller when in the in position and causing the pins to extend beyond the periphery of the roller when in the out position.

5 27. In a writing machine, a pin feeding mechanism, said pin feeding mechanism having an operative and an inoperative position, said pin feeding mechanism including a plurality of pins, some of which engage the paper when in operative position, and a cam having a contracted position and an expanded position, said cam when in the expanded position causing some of said pins to engage the paper, and when in the contracted position guiding the pins in a path out of contact 10 with the paper.

15 28. In a writing machine, a platen, a pin feeding mechanism associated with said platen, said pin feeding mechanism including a plurality of pins, and a cam having a relative movement with respect to said pins, said cam having two positions, one position of the cam guiding the pins in a path entirely on the inside of the writing surface of said platen and the other position of said cam causing the pins to travel in a path 20 passing beyond the surface of said platen.

25 29. In a writing machine, a roller, a pin feeding mechanism associated with said roller, said pin feeding mechanism including a pair of cam sectors, one of which has an arcuate cam surface 30 concentric with the roller, the other sector having an out position and an in position, said other sector when in the in position having its cam surface substantially concentric with the stationary cam surface and when in out position cooperat- 35 ing with the stationary cam surface to form a substantially oval cam surface.

30 30. In a writing machine, a roller, a pin wheel feeding mechanism carried by said roller, said pin wheel feeding mechanism including pins 40 mounted in said roller, and a pair of cams for positioning the pins with respect to the periphery of the roller, one of said cams causing the pins to travel in a path concentric with and within the periphery of said roller, the other cam having 45 two positions one of which causes the pins to travel in a substantially circular path and the other of which causes the pins to extend beyond the periphery of the roller so as to engage the writing material.

45 31. In a writing machine, a roller, a pin wheel feeding mechanism associated with said roller, said pin wheel feeding mechanism including a plurality of feeding pins, arranged radially in said roller, and a pair of cams for positioning 50 the pins with respect to the periphery of the roller, one of said cams including an arcuate portion for causing the pins to travel in an arcuate path within the periphery of the roller, the other cam having two positions, one of which causes the 55 pins to travel in a circular path within the periphery of the roller, and the other causing the pins to extend through the periphery of the roller so as to engage the writing material, and resilient means for biasing said movable cam into one 60 of said positions.

55 32. The combination with a revolute platen roll for a writing machine, including axially adjustable sections, retractile paper engaging means mounted within the roll and projectable radially beyond the periphery thereof intermediate the axially adjustable sections, said paper engaging means being retained in retracted position by the relative adjustment of said sections toward each other.

60 33. A platen roll for a writing machine includ-

ing an axially adjustable section, a retractile radially disposed pin carried by the platen roll engageable in spaced holes in the record material fed about the platen roll for positively advancing the record material, said pin being overhung when in retracted position by the axially adjustable section of the roll and adapted to be projected radially beyond the periphery of the roll upon retraction of said adjustable section.

65 34. The combination with a revolute platen roll for a writing machine of a series of reciprocating radial feeding pins carried thereby for engagement in spaced holes in record material to be fed about the roll, and an expansible and contractile control cam for actuating the pins, the pins being maintained wholly within the periphery of the roll upon contraction of the cam, and progressively projected therebeyond by the rotation of the roll upon expansion of the cam.

70 35. A platen roll for a writing machine, a series of radially disposed feeding pins carried thereby for engagement in punched holes in record material for positively advancing the material about the platen roll, non-rotatable means for progressively projecting the pins into engagement with the material and retracting said pins by the rotation of the roll, and means for maintaining all of the pins in retracted position to permit the use of the roll for frictional feeding of the material.

75 36. A platen roll for a writing machine, a series of radially disposed feeding pins carried thereby for engagement in punched holes in record material for positively advancing the material about the platen roll, and a non-rotatable mounting for the pins, said mounting being expansible and contractile so that the pins may be rendered inoperative upon contraction of said mounting.

80 37. A revolute platen roll for a writing machine, a series of reciprocating feeding pins carried thereby for engagement in punched holes in record material being fed about the platen roll for positively advancing such material, non rotatable means for progressively reciprocating the pins into engaging positions beyond the periphery of the roll, and a mechanism causing said means to actuate the pins in a path within the periphery of the roll, whereby the roll may be used for frictionally feeding material independently of the pins.

85 38. A platen roll for a writing machine having a pin feeding device having operative and inoperative positions, including an axially adjustable section, said section rotating in unison with said platen when in one position, and means for preventing the rotation of said section with said platen when said section is in the other position, said section being in one of said positions when the pin feeding device is operative and in the other position when the feeding device is inoperative.

90 39. In a writing machine, a rotary platen, a pin wheel feeding mechanism associated with said platen, adapted to feed the writing material circumferentially around said platen, said pin wheel feeding mechanism having an operative and an inoperative position, the pins of said pin wheel feeding mechanism extending beyond the periphery of said platen when in operative position, and non-rotatable means mounted within the platen for holding the pin wheel mechanism in either position, said means being adapted to adjust all the pins below the periphery of the platen when in inoperative position.

95 40. In a writing machine, a rotary platen, a pin wheel feeding mechanism associated with

said platen, said pin wheel feeding mechanism including a plurality of pins radially disposed with respect to said platen, means including a stationary member and an adjustable member 5 for adjusting the pin wheel feeding mechanism to operative position with the pins extending beyond the periphery of the platen, said means being adapted to retract the pins wholly below the periphery of the platen to inoperative position.

41. In a typewriting machine having a rotary platen, a pin wheel feeding device adapted to feed manifolded continuous forms around said platen associated therewith, said device including 15 means common to all the pins of said pin wheel feeding device, said means being adjustable to operative position projecting the pins beyond the periphery of the platen within an area less than the circumference of the platen and adapted to 20 be retracted to inoperative position when the pins are wholly beneath the peripheral surface of the platen.

42. In a writing machine, a pin feeding mechanism, said pin feed mechanism having an operative and an inoperative position, said pin feeding mechanism including a plurality of pins, some of which engage the paper when in operative position, and adjustable means simultaneously engaged by all the pins for changing the feed 30 pins to either operative or inoperative position, below the surface of the platen.

43. In a writing machine, a platen, a pin feeding mechanism associated with said platen, said pin feeding mechanism including a plurality of pins, and a non-rotatable adjusting means within the platen having a relative movement with respect to said pins, said adjusting means having two positions, one position guiding the pins in a path entirely below the writing surface of said 35 platen, and the other position of said means causing the pins to perform in a path passing beyond the surface of said platen.

44. The combination with a revoluble platen for a writing machine, around which paper is 45 fed, including axially adjustable feeding means associated therewith, said paper feeding means being retractable to inoperative feeding position below the writing surface of the platen and being projectable radially to operative position 50 beyond the writing surface of said platen, said feeding means adapted to be locked in either position for the purposes described.

45. A rotary platen for a writing machine including a radially disposed pin carried by the platen engageable in spaced holes in the record 55 material fed about the platen for positively advancing the record material, said pin having manually operated means having a guide forming a closed loop for adjusting it to operative or inoperative position above or entirely below the writing surface of the platen, said means being of a selective character.

46. A rotary platen for a writing machine, a series of radially disposed pins associated therewith for engagement in punched holes in record material for positively advancing the material about the platen, means common to all the pins for progressively projecting the pins into engagement with the record material and retracting said pins from engagement therewith, and means common to all the pins for maintaining the same in retracted position to permit the use of the platen for frictional feeding of record material.

47. A rotary platen for a writing machine, a series of radially disposed feeding pins opera-

tively connected thereto and adapted to engage in punched holes in record material for positively advancing record material about the platen past a printing point, and an adjustable mounting common to all the pins by which the pins may be adjusted to inoperative position entirely below the writing surface of the platen.

48. A rotary platen for a writing machine, including an axially adjustable pin wheel feeding means operatively connected therewith, said pin wheel feeding means rotating in unison with said platen, said pin wheel feeding means being adjustable to operative position for engagement with punched holes in manifolded paper beyond the writing surface of said platen and being adjustable to inoperative position below the writing surface of said platen, and friction feeding mechanism supplying paper past the writing position when the pin feeding means is in inoperative position.

49. A platen roll for a writing machine, including an axially adjustable section, a guide carried by said roll, said guide having an in position and an out position, retractile feeding pins associated with said platen roll and guided by the 100 guide, said feeding pins engageable in spaced holes in the record material fed above the platen roll for positively advancing the record material when said guide is in the out position, said feeding pins being covered by said adjustable section when the 105 guide is in the in position, so as to present an uninterrupted writing surface when the guide is in the in position.

50. A rotary platen for a writing machine, including an adjustable pin wheel feeding device, 110 said pin wheel feeding device being operatively connected with said platen operating in unison therewith, said pin wheel feeding device, including a flexible guide common to all the pins, said guide having an in position and an out position, 115 said guide when in the in position making said pin wheel feeding device wholly inoperative by the feeding pins travelling below the writing surface of said platen.

51. The combination with a writing machine 120 platen of a traveling series of material engaging pins associated therewith, means for actuating the pins through a circuitous path of travel, a variable guide simultaneously engaged by all the pins, by adjustment of which the path of travel of the pins may be extended and contracted, and control means for the guide.

52. The combination with a writing machine 125 platen of a traveling series of material engaging pins associated therewith, means for actuating the pins through a circuitous path of travel, a variable guide simultaneously engaged by all the pins, by adjustment of which the contour of the path of travel of the pins may be changed, and adjusting means for said guide.

53. The combination with a writing machine 130 platen, of a traveling series of reciprocatory material engaging pins, associated therewith, means for actuating the pins through a circuitous path of travel and variable controlling means simultaneously engaged by all of the pins for varying the extent of reciprocatory motion thereof during their circuitous travel.

54. The combination with a writing machine 135 platen of a rotary series of reciprocatory material engaging pins associated therewith, a yielding guiding member therefor and means for changing the shape of the guiding cam to correspondingly change the degree of reciprocation of the pins.

55. The combination with a writing machine 140

platen and a rotary series of reciprocating material engaging pins carried thereby, a yielding guide member for the pins and means for expanding and contracting the guide member to change the rotary course of the pins.

56. The combination with a writing machine

platen and a rotary series of reciprocating material engaging pins carried thereby, a yielding guide member for the pins and means for varying the shape of the guide member to change the rotary course of the pins.
